OF ATHENS, GEORGIA, ASSIGNEES, BY MESNE ASSIGNMENTS, TO WESTERN ELECTRIC
COMPANY, INCORPORATED, A CORPORATION OF NEW YORK.

AUTOMATIC TELEPHONE-EXCHANGE SYSTEM.

1,232,338.

Specification of Letters Patent.

Patented July 3, 1917.

Application filed January 18, 1908. Serial No. 296,885.

To all whom it may concern:
Be it known that we, JACOB WILLIAM LATTIG and CHARLES LANE GOODRUM, citizens of the United States, residing at Rochester, in the county of Monroe, State of New York, and Athens, in the county of Clark and State of Georgia, respectively, have invented certain new and useful Improvements in Automatic Telephone-Exchange Systems, of which the following is a specification, reference being had therein to the accompanying drawing.

Our invention relates to telephone exchange systems, and particularly what are known as automatic telephone exchange systems, and has for its object the improvement thereof in the manner and in regard to the features hereinafter set forth.

Heretofore, most automatic systems with which we are acquainted have provided what is commonly called a first selector switch for each line. In some systems this first selector switch performed the function of actually selecting the thousands digit of the whole number of the subscriber wanted, and finding an idle trunk corresponding thereto; in other systems, including some of our own design, the first selector has been simplified and used merely for the purpose of selecting an idle trunk to another selector switch through which the desired operation might be performed. The second of these methods has proved to be the better in practice, the line switch then ceasing to be a true first selector, and becoming what is called an "A" switch, through which the line calling is put upon a first selector. This, however, is only one step toward simplification; and in the present case we shall set forth the second step, by which the lines are not provided with any switches, but merely with terminals in what we shall call "finders," there being only so many of these "finders" as are actually required to take care of the number of lines calling at once. Ten percent of the number of lines is probably sufficient, and in many cases a lower percentage of finders will suffice.

In conjunction with our "finder" switches we use what we shall term "starters," the function of which is to segregate each finder switch as it becomes busy, by picking up a calling line, and simultaneously to render active the next finder switch in order, thus

distributing traffic over a plurality of switches. By this means the first incoming call is picked up by the first idle finder switch; the second incoming call is taken up by the next idle finder switch, and so on, without interference. Each finder switch constitutes the answering terminal for a trunk line leading to a first selector or "A" switch, and thence the connections and circuits being the same as in our former systems, to which more detailed reference will be made hereinafter. The present invention does not reside in the system of switches or circuits employed from the first selector onward, but resides particularly in the arrangement and circuit connections of the starter and finder switches.

By our present invention each line is provided with a relay which is operated when the line calling becomes energized and renders active the controlling circuit of the first idle finder switch, passing thereto through certain contacts controlled by the starter switch. The finder switch responds by starting the starter switch, and at the same time the starting circuit is altered so that the starting impulse is reduced to momentary duration only. The starter switch moves one step, cuts off the finder then in operation from the starting circuit, and puts the next idle finder thereon. The selected finder switch, in the meantime, moves around until it finds the terminals of the line calling, whereupon it stops and connects that line to a trunk passing to the first selector switch. At the close of the conversation, the subscriber in hanging up restores the finder switch, as well as all the selector switches, by the same operation.

Referring to the drawings, Figure 1 is a top plan view of a B or first selector switch; Figs. 2, 3, 4 and 5 are details thereof; Fig. 6 is a top plan view of the G or connector switch and Fig. 7 is a detail view of its banks; Figs. 8, 9, 10, 11 and 12 are continuing diagrams showing respectively the circuits of the starter switch A¹, finder or A switch, first selector or B switch, second selector or C switch, connector or G switch and the line apparatus; Figs. 8^a and 8^b are associated diagrammatic views showing a plurality of the finder switches illustrated in Figs. 8 and 9 and the starter switch co-operating therewith. In these figures three

separate instrument circuits are shown served by four finder switches on each of which blank contacts are shown illustrating terminals of other circuits of which there 5 would be upward of fifty, representing an equal number of lines greater than the number of switches. Fig. 13 is a diagrammatic view showing a separate starter switch and illustrating its operation in connection with 10 a group of finder switches.

Referring to Fig. 1, E is a base plate of metal, rectangular in shape and divided along the line e^1 of its upper end, leaving an upper rim e to form a base for the contact 15 banks F. Upon this base a row of socket contacts H are mounted in insulation, with which coöperate the contact terminals h mounted in a strip on the base E. These 20 terminals h are used to complete the circuits from the cable in the racks to the magnets shown on the base E.

The contact banks F are formed as an arc of a circle subtended by an angle somewhat less than 180 degrees, and concentric with 25 the center or axis b of the switch spindle. In the banks are the broad contacts 48, and the individual trunk contacts m^6 , which will be pointed out hereafter in referring to the diagrams.

30 Extending across the upper end of the plate E is a bridge e^8 drilled at its middle point to receive the coned end of the switch spindle b . Directly in line with the opening in the bridge a similar opening is formed 35 in the plate for the other end of the spindle. In a box secured around the foot end of this spindle is the coiled spring b^9 , which serves to return the spindle to initial position when released, as hereinafter described. 40 Upon the spindle are mounted the ratchet wheels b^4 and b^5 , the stop ratchet wheel b^{50} , and the wipers b^1 , b^2 , b^3 . These, and particularly the wipers, are insulated. Each wiper has an arc b^{15} , extending around the 45 spindle, and upon these arcs, which serve as collector rings or segments, rest the ends of contact springs b^{20} , carried in insulation on the right-hand side of the bridge e^8 , as shown in Fig. 1, each spring having a tail b^{11} for the attachment of its circuit wire, and an extension b^{12} which receives the wiper when turned all the way around to clear it from the bank contacts and hold it in proper position for reengagement there- 50 with, this clearing being necessary when the plate E and its attached parts are removed from the switch. To facilitate the removal and replacing of the plate in proper alignment with the base e of the banks, we pro- 55 vide a pair of guide tongues e^2 , attached to the plate e and overlying the plate E when in position. The bank as a whole is carried on four posts p , best shown in Figs. 3 and 5, and each bank of contacts is built up of 60 insulating segments with the contacts ra-

dially interposed between them, the whole being held together by upper and lower seg- 65 mental metal plates f secured by through- bolts or screws f^1 .

Coöperating with the ratchet teeth b^6 on 70 the wheel b^4 is the pawl b^{16} on a dog b^{14} pivoted in a yoke attached to the base-plate E as shown in Figs. 1, 2 and 3. The dog has a joint in the middle, and a spring nor- 75 mally tending to throw it up with the ratchet engaging the teeth b^6 . Coöperating with this ratchet to form an escapement, is the armature lever b^{13} of the magnet M^{10} , this lever having a chisel edge to enter the teeth, and a bar b^{15} to withdraw the ratchet as the 80 edge enters, by forcing up the tail b^{14} of the dog.

Opposite the ratchet the dog has a toe 85 b^{17} with which coöperates a hook on the end of the spring b^{18} carried on the end of the armature lever of the release magnet M^5 . When this armature is attracted, the ratchet 90 b^{16} being up, the spring reaches up, the hook takes hold of the toe and pulls down the dog, permitting the spring b^6 to return the 95 spindle b and all its arms to zero position as shown in Fig. 1.

In order to step the wheel b^4 around, the 100 armature of the magnet M^7 carries a pawl b^7 pivoted at b^8 and having an angle stop b^9 coming against a fixed stop b^{90} on the bridge e^8 when the magnet is deenergized as shown 105 in Fig. 1. As the magnet M^7 is energized, its vertical lever is thrown to the left, a projection on the lower part thereof comes against the spring b^{18} to remove it from the toe b^{17} and permit the retaining pawl to rise into engagement with the teeth b^6 , the stop b^9 at the same time leaves the fixed stop b^{90} , the spring b^{80} swings the pawl b^7 around 110 the pivot b^8 until its point engages the teeth on the ratchet wheel b^6 , each tooth on this wheel moving the arms around over five contacts m^6 at a jump, while each tooth b^6 moves the arms over one contact singly. As 115 the pawl b^7 pushes the wheel b^6 around the toe b^{51} on the upper end of the armature lever comes over in the path of and serves as a stop for the teeth on a second wheel b^{50} , furnishing a positive stop for each step in 120 the rotation.

Each arm has an annular collector ring, b^{19} , as stated, upon which rests the spring b^{20} . When it is desired to remove the switch body from the rack, the arms are turned 125 all the way around until they rest on the fixed contacts b^{12} , and come away with the body plate E.

Further description of the B and C switches is unnecessary in view of the state- 130 ment of operation hereafter, and the full- ness of the illustration. It is to be under- 125 stood that we intend to claim everything we have shown as our invention.

Referring now to Figs. 6 and 7, we will 130

point out briefly the distinctive features of the G switch shown herein. The only difference between this switch and the B and C switches, in essentials, is in the number of switches, in essentials, is in the number of relays they carry. Each of them has the same kind of a base-plate E as that already described. Each has a similar bridge e^a and each has its own spindle and arms. This switch G has ten contacts if ten per cent. 10 of connective apparatus is required, and twelve if twelve per cent. There is no necessity for a double movement; there is only a single actuating magnet, M^{24} , and a release magnet M^{23} .

15 The arrangement of the switch base E and the frame carrying the bank contacts, as well as the sliding contact spring connections between the two, is the same as in the B switch.

20 The relays employed are, with one exception, of the form shown in Fig. 4. The exception is shown in the relay M^{33} illustrated at the bottom of Fig. 2, and in the middle of the bottom of Fig. 1. This is a polar relay, having a straight armature s resting on a knife edge on the end of its core and tilting one way or the other according to the direction of current and consequent magnetic polarity of the iron core and armature. Straddling the entire winding is a magnet S secured at its neutral point to the inactive end of the core. On one arm of this magnet is secured a leaf spring s^1 having its end bent up and resting upon the 25 raised middle portion of the armature over the knife edge, so as to hold the armature in position. Along the other arm of the magnet we secure a contact spring s^2 forming one side of the circuit to be controlled, the armature forming the other.

30 The escapement magnet M^{10} , and release magnet M^5 , of the selector switches, and the release magnet M^{23} of the connector switch, in addition to being working magnets, each 35 controls contacts in circuits, the functions of which will be further described. In each case the contacts are secured to the frame of the magnet and are actuated by a lever, one end of which forms the armature of its respective magnet.

Referring now to the circuits, first of all it will be observed that we have shown at the subscriber's station what are known as standard Strowger circuits and apparatus. 40 This substation circuit needs no description for those skilled in the art, but it should be understood that we can substitute other suitable means for operating it. The simplest form of apparatus we can use at the substation comprises two push-buttons each connecting one side of the line to ground when depressed, and an ordinary common battery talking circuit. To work the system herein illustrated the successive sets or groups of 45 impulses are sent by grounding one side of

the line in succession the desired number of times, and grounding the mate side of line once between the sets or groups. In the Strowger apparatus this separating of the sets or groups of impulses is done automatically.

70 The subscriber's line terminates in the central office in relays which when energized make active a starter switch A^1 , (Figs. 8^a and 9), which in turn starts another switch A, (Fig. 9). This second switch A picks out the calling line and connects it to a B switch with which it is associated. The B switch steps around its arms in obedience to impulses, each step taking five contacts, and each five contacts representing five trunks to the next order of switches. When the desired group is reached, the single impulse over the other side shifts the energizing circuit, and the escapement magnet comes into 80 play, stepping the arms back one contact at a time until an idle trunk of the group is reached. It should be observed that the return movement is produced by the ordinary retracting spring.

85 Having extended by these successive steps the calling subscriber's line through to the connector G, shown in Figs. 11, 6 and 7, the connector is permitted to select the called line with which connection is desired, by 90 actuating the connector the required number of times by impulses from the calling party's station.

95 The battery connections throughout the 100 circuits are from ground to both sides of the line normally, and not until the called subscriber answers is talking current cut back to the calling subscriber. By this means we are enabled to regulate the operation of registering devices by employing the polarized 105 relay M^{33} , (Fig. 8) arranged in a circuit terminating in the contacts m^{20} , with which the wiper a of switch A co-operates.

110 The balance of the circuits will be better understood from a statement of operation, tracing one call in its progress through all the switches. The operation of the system is as follows:

115 In tracing a call through from telephone A (Fig. 8) to telephone B (Fig. 12), the first operation is that of subscriber A removing his telephone from its hook, thereby closing contact springs o^1 and o^2 , which are connected to the main line wires by the following route: wire 3, spring o^1 , spring o^2 , 120 wire 5, transmitter T, winding I of the induction coil, wire 1 (one) to line 12, thus closing the line circuit. This circuit may be traced by the following path: 11, 159, relay M^{24} , 158, spring 178, spring 179, wires 152, 125 153, to the grounded side of battery U, through battery to wire 155, relay M^{33} , wire 150, spring 176, spring 177, wire 157, through mate line 12 to wire 1, completing the circuit through the A subscriber's tele- 130

phone, as above described. This action energizes relays M^{34} and M^{36} . In closing, the relay M^{36} operates its armature, opening springs 173 and 174 and closing springs 174 and 175. Spring 175 is connected to ground through wires 161 and 153, and when in contact with the spring 174 throws ground on wire 154. The object of this is to prevent any other subscriber from calling in to this subscriber, while he is in the act of making a call. This relay M^{36} in operating also breaks the springs 170 and 171, and closes springs 171 and 172. Contact spring 171 is connected to the grounded side of battery through wires 152 and 153, thus connecting grounded battery to wire 160, contact springs 180 and 181, wire 9. While this action is occurring relay M^{34} is also energized, but being so constructed that it operates more slowly than relay M^{36} it does not open the circuit between springs 180 and 181, which we have just described as completing a circuit from ground to wire 9 until the circuit of relay M , Fig. 9, has been closed by the following path: wire 9, contact spring a^6 , contact m^{28} , wires 24 and 15, through relay M to wire 16 to battery. When relay M operates, by reason of the momentary grounding of its circuit over the wire 9, it closes springs 183 and 184, also springs 189 and 190. Spring 183 is connected to ground through wire 25, contact spring a^2 , and wire 195. Thus it will be seen that ground will be thrown on spring 184 and on spring 189, through wires 21 and 25. This ground on spring 184 can be traced through wires 25 and 15, through relay M and wire 16, thus keeping it energized. The ground on spring 190, above described, will energize magnet M^2 , through wire 18, contact springs 191 and 192, wire 17, through magnet M^2 , wire 14, battery, giving to the motor magnet the initial impulse to advance the finder switch one step, additional steps being imparted by which wiper a^2 engages a grounded contact in the bank m^{23} and until said wiper engages the terminal of a calling line from which the ground has been removed.

M^2 is a motor magnet of a switching mechanism similar to our other switches. This switch will hereinafter be referred to as the finder switch. When, therefore, M^2 is energized, it revolves shaft A through the instrumentality of pawls and dogs, not shown in this diagram. Shaft A carries a series of wipers over contact points until wiper a^2 ceases to find a contact that is grounded. As soon as wiper a^3 passes from contact a^6 to the grounded contact segment a^7 , and actuates the starter by throwing ground through wires 13 and 19, contact a^4 , wire 7, through magnet M^{32} , wire 8, contact springs 193 and 194, wire 8 to battery. M^{32} is the motor magnet of another switch, which will hereinafter be called a starter switch, which re-

volves its shaft A¹ similar to the other just mentioned. This moves wipers a^4 and a^5 over contact banks m^{25} and m^{26} , respectively. These contacts are connected to other finder switches in the same manner as contacts m^{28} and m^{29} are connected to the finder switch, as illustrated particularly in Figs. 8^a and 8^b and 9. Now, referring to Fig. 8, it has been above explained that when relay M^{36} has been energized the contact between springs 170 and 171 is broken, thus taking the ground connection from spring 170. This spring 170 is connected by wire 151 to contacts m^{23} . These contacts are the multiple bank contacts in front of four separate finder switches. A greater or less number of finder switches may be used as described. Therefore, if any finder switch has been started, it will immediately stop on one of these contacts. In this case, the finder switch, Fig. 9, will stop with its wipers on one of the multiple contacts m^{23} , appearing in the bank of contacts in front of this finder switch for this particular subscriber's line.

We have already shown how the starter switch started the finder switch in this instance. It will now be plain that this same starter switch can start other finder switches, shown in Fig. 8^b, such finder switches being connected to contacts m^{25} and m^{26} . Should there be sufficient calls from other subscribers to step this starter switch to the last set of contacts, it will be released as follows: the interrupter X is so arranged that it will throw ground impulses on contact m^{30} , thus it can be seen that when wiper a^{50} reaches contact m^{30} , grounded battery will flow through contact m^{30} , wiper a^{50} , wire 6, release magnet M^1 , wire 8, to battery, thus energizing release magnet M^1 allowing the wipers on shaft A¹ to return to their normal position on contacts m^{29} and m^{28} .

We have now shown that the finder switch, Fig. 9, has been caused to operate and has placed its wipers a^4 , a^5 , on contacts m^{20} , m^{21} , thus connecting lines 29 and 30 respectively to lines 11 and 12 leading back to the calling subscriber.

When the finder switch, (Fig. 9) stops on the contacts above described, relay M^{36} , (Fig. 8) will be energized as follows: spring 186, (Fig. 9), being in contact with spring 185 which is connected to ground through wire 23 will allow grounded battery current to flow through wire 22, wiper a^{20} , contact m^{23} , wire 200, through relay M^{36} , wire 155 to battery. When this relay is energized the contact between springs 176 and 177 and between 178 and 179 is broken, thus breaking the ground connection from spring 178, wire 158, relay M^{34} , wire 159; also breaking the connection to relay M^{34} , through wire 150, springs 176, 177, wire 157. The object of these breaks is to free the line wire 11 and mate 12 from all connections with the appa- 130

ratus shown in Fig. 8, and also to deenergize relays M^{34} and M^{35} .

This completes the necessary switching operation to connect the talking circuit from subscriber A to the "B" switch or first selector.

This also closes the busy trunk by the engagement of the wiper a^3 with contact a^7 thus energizing magnet M^4 over the following circuit: ground, contact a^7 , wiper a^3 , wires 13 and 19, contacts 188 and 187, wires 20 and 34, wiper b^3 , wire 41, magnet M^4 , wires 40, 54, 52 and 51, battery and ground.

Now, by grounding wire 3 at the subscriber's station the required number of times to select the desired trunk leading from the first selector to the second selector or to the connector switch in the event a second selector is not employed will cause magnet M^8 to be operated. This circuit may be traced as follows: starting from subscriber's station, ground, wire 3, wire 11, a^1 , wire 29, spring 71, contact 72, wire 73, winding of magnet M^8 , wire 51, battery, ground. M^8 in operating closes the following local circuit: ground, main battery, wires 51, 52, magnet M^7 , wire 53, spring 59, spring 60, wire 61, spring 62, contact spring 63, wire 65, ground.

Magnet M^7 by ratchet arrangement, turns shaft b , to which wipers b^1 , b^2 and b^3 are attached, causing the same to turn with shaft b . Magnet M^7 in turning shaft steps it over five contacts m^7 (Fig. 10). Now by the movement of the spindle b , the rotation of which has been previously started, the wiper b^3 moves into engagement with contacts m^8 .

At the same time wiper b^3 cuts out the wire 34 and engages a contact segment connected to the wire 48, against which it rests after moving out of its normal position, allowing the magnet M^4 to be energized by current in the following holding circuit: ground, main battery, wires 51, 52, 54, and 40, magnet M^4 , wire 41, wiper b^3 , wire 48, contacts 47 and 46, magnet M^5 , wire 44, contacts 77 and 78, wire 79 to ground.

Therefore, M^4 would continue to hold up even though the spindle b was being turned by magnet M^7 . We will now close the circuit from ground once at subscriber's station over wire 1, (one) wire 12, contacts m^{21} , wiper a^{11} , wire 30, contacts 74 and 75, wire 76, winding on M^9 , wire 50, battery to ground; this operation of the magnet M^9 would open contact between springs 77 and 78, depriving M^4 of its source of ground, which would then, if the wiper b^3 of the switch was at that time standing on a ground or busy contact of m^8 , continue to hold up M^4 . If then the wiper b^3 does not happen to have a source of ground, M^4 would therefore have to release or drop back, extending the lines that it had just previously opened to the first selector switch (Fig. 10) and cutting off the magnets M^8 and M^9 that it

had just previously connected. If, however, the wiper b^3 was on a grounded contact, then winding of M^9 would hold up over this ground as well as M^4 . We would also then have a circuit through M^{10} , starting at m^6 , 70 supposing it was grounded, b^{30} , wire 43, winding of M^5 , wire 44, spring 77, contact spring 80, wire 81, wire 82, winding of M^9 , wire 50, battery, ground. We then have a circuit through magnet M^{10} , in parallel with 75 the circuit of M^9 , from wire 81, spring 84, contact spring 85, wire 86, winding of M^{10} , wire 87, wire 50, main battery, ground. Magnet M^{10} controls an escapement connected with shaft b and when energized 80 makes and breaks its own circuit like a buzzer. Shaft b being under tension of a retractile spring drops back one contact with each step. So in this manner we travel backward over contacts m^6 so long as b^{30} 85 can find ground. So as soon as wiper b^{30} loses ground we then notice that M^4 , M^9 lose their circuit, consequently releasing, and in consequence M^{10} also is disconnected from battery and will, therefore, vibrate its armature no longer. Therefore, all the relays of B switch are normal. A circuit may now be traced from contact m^6 back through b^{30} , wire 43, M^5 , wire 44, spring 77, spring 78, wire 79, ground. Since wiper b^{30} , on m^6 is 90 grounded and current flows over a circuit from contact m^6 , wire 49, (Fig. 10) wire 88, c^2 , wire 89, M^{12} , wire 90, main battery, ground, relay M^{12} is thereby caused to operate, causing it to open its normally closed 95 contacts and close its normally open contacts, opening wire 91 from 94 and wire 92 from wire 93, and cutting wire 91 onto relay M^{14} and wire 92 onto relay M^{15} . Now, therefore, when wire 3 (Fig. 8) at subscriber's station is grounded one or more times to select the trunk leading to the second selector switch, it will be seen that relay M^{14} is operated, which acts to energize 100 M^{17} with each impulse of current causing it to turn the spindle c a sufficient distance 105 to move its wipers through a space of five contacts.

When the shaft c takes its first step, the brush c^2 passes from the terminal of wire 88 115 on to the terminal of wire 480, thus interrupting the original energizing circuit for relay M^{12} but completing a substitute circuit from battery, through wire 90, winding of M^{12} , wire 89, brush c^2 , wire 480, contacts 120 470 and 460, wire 460^a, winding of relay M^{13} , wire 440, to ground through contacts m^{61} and m^{65} .

M^{14} is similar in action to M^8 and is capable under proper condition of being 125 actuated by successive impulses of current from the calling subscriber's station whenever the line 3 is grounded, which condition exists until the relay M^{12} is deenergized. Now, grounding wire 1 (one) at subscriber's 130

- station once causes M^{15} to be operated by current in the following circuit: (Fig. 8) ground, wires 1, (one) 12, contact a^{11} (Fig. 9) wire 30, contacts 74, wire 30, contact m^7 5 (Fig. 10) wire 92, contacts 92^a, and 15^m, wire 151, magnet M^{15} , wire 152 to battery and ground. The energization of M^{15} interrupts the substitute circuit for magnet M^{12} but a second holding circuit now extends 10 from wire 460^a, through wire 430 and wiper c^{20} to contact m^9 . The energization of M^{15} also completes a circuit from battery, through wire 152, right winding of M^{15} and the winding of M^{16} in parallel, contacts m^{62} , 15 m^{61} , wire 440, winding of relay M^{13} , wire 430 and wiper c^{20} to terminal contact m^9 . As the original energizing winding for M^{15} passes through normally open contacts of relay M^{12} , it will be seen that the continued 20 energization of M^{12} , M^{15} and M^{16} is dependent upon the contact m^9 on which brush c^{20} rests, being grounded. If the trunk represented by this contact is idle, no ground will be on contact m^9 and the above relays will 25 become deenergized and no further movement of the switch shaft c will take place. If, however, a multiple of the contact m^9 is engaged by another selector, m^9 will be connected to ground through said multiple, 30 the wiper c^{20} of the switch thereon, wire 430, winding of M^{13} and contacts m^{61} , m^{65} to ground, thus relays M^{12} and M^{15} will be maintained energized and the magnet M^{16} , which interrupts its own circuit by every 35 energization at contacts m^{64} , will be intermittently energized to permit the shaft c to rotate backward step by step until wiper c^{20} fails to find ground on the terminal contact m^9 of an idle trunk, when the circuit 40 for relays M^{12} , M^{15} and the magnet M^{16} will be interrupted as before described. The deenergization of relay M^{15} by closing contacts m^{65} , m^{61} places ground on the contact m^9 , thus making the trunk busy. This circuit 45 may be traced over the following path: (Fig. 10) ground m^{65} , contact m^{61} , wire 440, magnet M^{13} , wire 430, wiper c^{20} , contact m^9 (Fig. 11) wire 95, wiper g^{30} , wire 96, M^{19} , wire 97, battery to ground.
- 50 We, therefore, see that M^{19} , will be energized, opening its normally closed contacts and closing its normally open contacts, causing wire 98 to be separated from wire 99 by contacts 199 and causing wire 100 to be separated from wire 101 by contacts 100^a. We also see that connected to wire 98 we have, magnet M^{21} , wire 102, spring 103, spring 104, wire 105 to main battery and ground. On wire 100 we have tapped magnet M^{22} , wire 106, spring 107, contact spring 108, wire 109, spring 110, contact spring 111, wire 112, wire 105 to main battery. Now, suppose that we ground wire 3 at subscriber's station the necessary number of times to operate the 55 selected connector switch to cause its wipers to take up the terminals of the called party's line. Each time wire 3 is grounded, a circuit is completed from ground at substation A over the upper talking strand of the line now complete through to wire 98, Fig. 11, 70 winding of magnet M^{21} , contacts 103 and 104 to battery and ground. Each energization of M^{21} completes a circuit from battery, through wire 98, contacts of M^{19} now energized, the winding of M^{24} , contacts of M^{21} 75 and contacts of M^{23} to battery, thus energizing M^{24} . Magnet M^{24} moves the shaft and its wipers forward one step or one set of contact terminals each time it is energized. It was just described how M^{19} was originally 80 energized through wiper g^{30} . This original circuit through g^{30} is broken with the first step of the shaft g but another circuit for relay M^{19} is now established, from battery, over wire 97, winding of M^{19} , contacts of 85 M^{19} and contacts of M^{22} , back to battery. Therefore as long as M^{22} remains normal, M^{19} will be held up and the shaft can be stepped around as far as desired. Now grounding the lower talking strand of the 90 line at substation A completes a circuit over the lower talking strand of the line, through relay M^{22} , contacts 107, 108, contacts 110 and 111 to battery and ground. This will operate M^{22} , interrupting the circuit just traced 95 for the relay M^{19} . If the called line is idle, M^{19} will become deenergized, extending the talking strands 98 and 100 through to the brushes of the switch g . All of the relays will now be in their normal condition. Now, 100 we will suppose that the contact m^{19} on which the shaft placed the wiper g^3 was busy, (being grounded to operate M^{23} to clear the line during the time connection is established therewith) we would then have ground 105 on this contact so, therefore, considering ground on the contact m^{19} , wiper g^3 , wire 121, wire 117, spring 116, contact spring 115, wire 114, wire 113, M^{19} , wire 97, battery to ground. Therefore, if this line is busy, magnet M^{19} will remain held up and will not release even though M^{22} is operated, which will prevent any one from coming in on a line that is busy. Now, again, supposing that the line was not busy and the connector switch 115 did cut through, we will notice that when M^{19} and M^{22} drop back, we have ground (Fig. 11) by wire 120, spring 119, contact spring 118, wire 117, wire 121 to g^3 on to a contact m^{19} (Fig. 12) wires 122, 123, M^{28} , 120 wire 124 to main battery and ground, which causes M^{28} to operate. Wires 125 and 126, (supposed to be the called subscriber's individual line); are thus cleared from any connection with A^0 , representing the multiple contacts of said line in front of the finder switches. Now, we therefore have gone through and connected with the desired line (it is understood that wires 125 and 126 extend to subscriber's station). We 130

now know with M^{19} in its normal condition and shaft g off normal, that g^1 engages the interrupter which makes and breaks the ground, and thereby M^{26} is caused to be drawn and held for an instant then released, then again drawn up and released, etc., as long as the conditions just described are true, over the following circuit: ground, interrupter 300, wiper g^1 , relay magnet M^{26} , springs 301, 302, 303 and 304, wire 305, to main battery. Thus M^{26} operated in this manner, as shown by the contacts, throws a ringing current out to the called subscriber, ringing his telephone intermittently until he answers or until the calling party hangs up. Now, supposing that the called party answers, it will be noticed that M^{27} is tapped on to one side of the line, the other side of the winding going through wire 105 to main battery. It will also be noticed that M^{25} is tapped on to the other side of the line and the other side to ground. So, therefore, the called party in taking his receiver off the hook causes M^{25} and M^{27} to act, closing their normally open contacts and opening their normally closed contacts. It will be noticed that M^{21} and M^{22} have their circuits open when M^{25} acts. It will also be noticed that M^{18} and M^{20} have their circuits normally open, but are closed as soon as M^{27} acts. The circuit of M^{18} and M^{20} is as follows: ground, wire 320, magnet M^{18} , closed contact springs on magnet M^{27} to the side of the line represented by 98 back through the several switches to subscriber's station, thence by the other side of the line to wire 100, contacts on relay M^{27} , to relay M^{20} and main battery. Therefore, the called party in taking his receiver off has done two things: cutting off M^{21} and M^{22} and cutting on M^{18} and M^{20} , and in this way has given the calling party what we might term "talking current." Now after the conversation is finished, if the called party hangs up first he causes both sides of his line to be grounded, and then the line side, 125, to be opened while the mate side, 126, is still grounded. To accomplish this the subscriber's sub-station is so constructed that it will hold ground an instant longer on the battery side of the line than it does on the grounded side of the line and which operates the release over the following circuit: ground, main battery, wires 306 and 316, springs 317 and 318, wire 320, springs 321 and 322, wires 323, 314 and 315, magnet M^{23} , wire 95, contact m^9 , wiper c^{20} , wire 430, relay M^{18} , wire 440, springs m^{61} and m^{65} and ground. By this operation, it will be seen that M^{23} drops back and that M^{27} holds up, closing the release circuit of M^{23} over the following path: (Fig. 11) battery, contact springs on M^{27} (now closed), contact springs on M^{25} (now closed), magnet M^{23} , bank contact m^9 , (Fig. 10) wiper c^{20} , wire 430, magnet M^{18} , wire 440, springs m^{61} , m^{65} to ground. M^{23} is in series with M^{18} and the latter operating causes its local magnet M^{11} to act by an impulse of current traversing the following path: (Fig. 10) battery, magnet M^{11} , contacts on M^{13} , wire 70 49, bank contact m^6 (Fig. 9) wiper b^{30} , wire 43, relay M^6 , wire 44, springs 77, 78, wire 79, ground. This circuit causes M^6 to act and close its local contact and energize the circuit of M^6 and M^3 , traced as follows: ground, wire 79, springs 38, 37, wire 33, magnet M^3 wire 14 to battery; also from wire 33, to wire 55, magnet M^6 , wire 54, 52, 51 to battery. Therefore, when M^2 loses its ground the entire set of switches is released to return to normal. If the calling party hangs up before the called party, then the calling party momentarily grounds both sides of the line, then breaks the line side, 98, which includes M^{18} , and the mate holding up M^{20} , over the following circuit: ground main battery B, wires 306 and 307, springs 308 and 309, wire 310, springs 311, and 312, wires 313, 314 and 315, magnet M^{23} , wire 95, contact m^9 , wiper c^{20} , (Fig. 10) wire 430, relay M^{18} , wire 440, springs m^{61} and m^{65} and ground. This closes the release circuit and causes the same operation just previously described. Now, supposing that the called party did not answer or was busy, then both sides of the line would be closed momentarily when the calling party hangs up, causing M^{21} and M^{22} to pull up at the same time which closes the release over the following circuit: ground, main battery, wires 306 and 324, springs 325, 326 and 327, 328, wire 315, magnet M^{23} , wire 95, contact m^9 , wiper c^{20} , wire 430, magnet m^{13} , wire 440, springs m^{61} and m^{65} to ground and thereby releases the switches.

Having thus described our invention, we claim:

1. In an automatic telephone system, the combination with a plurality of normally open instrument circuits having terminal contacts arranged in a switch bank, normally closed operating circuit branches and normally open starting circuit branches corresponding to each instrument circuit; terminals for the operating circuit branches arranged in a switch bank and wipers co-operating with said banks, of a line relay bridged to each instrument circuit and adapted to open its corresponding branch operating circuit, wipers co-operating with the different banks of contacts and electromagnetic operating mechanism for automatically advancing said wipers progressively which is adapted to be actuated by the closing of a branch starting circuit and to continue the movement of the wipers during the successive engagement of one of them with the terminals of closed operating circuit branches, a cut-off relay also associated with each instrument circuit adapted to open its line relay

- bridge, open branch circuits for the cut-off relays having terminals arranged in a switch bank and a wiper coöperating therewith having a circuit adapted to be closed to actuate the cut-off relay of the instrument circuit, on the terminals of which the other wipers of the switch mechanism are arrested.
2. In an automatic telephone system, the combination with a plurality of switching mechanisms comprising banks of terminals and wipers coöperating therewith, a plurality of instrument circuits connected in multiple to terminals in the several banks, branch operating circuits corresponding to each instrument circuit also having multiple terminals arranged in banks on the various switches and separate wipers on each switch coöperating therewith, of normally inoperative electromagnetic operating devices for each switch mechanism for automatically advancing its respective wipers as one of them successively engages the terminals of closed operating circuit branches, a starting mechanism for rendering said devices capable of operation, a local starting circuit for supplying an initial impulse of current to start a switch mechanism which is connected to said mechanism by the starting operating devices, normally open branches of said local circuit corresponding to each instrument circuit, means for closing them and opening the corresponding operating circuit branch and devices actuated upon the movement of each switch in turn to operate the starting mechanism to connect the local starting circuit to another switch.
3. In an automatic telephone system, the combination with a plurality of switching mechanisms comprising banks of terminals and wipers coöperating therewith, a plurality of instrument circuits connected in multiple to terminals in the several banks, of normally inoperative electro-magnetic operating devices for each switch adapted to be rendered active to advance their wipers while the latter continue to engage the terminals of open instrument circuits, a local starting circuit having normally open branches corresponding to each instrument circuit, two relays having different time constants bridged to each instrument circuit and controlling its corresponding branch operating circuit, the relay responding to current impulses with less rapidity being adapted to open said branch after the quickest relay has closed it, a switch-starter mechanism arranged in the local portion of the starting circuit comprising terminals for the electromagnetic operating devices of the several switches and a wiper coöperating therewith, the function of the starter mechanism being to successively connect the starter circuit with one or another of the switch operating mechanisms, and devices for actuating the starter mechanism.

4. In an automatic telephone system, the combination with a plurality of switches comprising banks of terminals and wipers coöperating with them, electromagnetic mechanism for advancing said wipers embodying a motor magnet having a normally open circuit, a controlling relay associated therewith for closing said circuit and a local starting and a local operating circuit over which current may be supplied to the relay at different times, of a starter switch mechanism comprising terminals for the controlling relay of each switch and having a wiper coöperating with said terminals, a plurality of instrument circuits connected in multiple to terminals in the various switch banks, branch starting circuits corresponding to each instrument circuits connected in multiple to terminals in the various switch banks, branch starting circuits corresponding to each instrument circuit terminating in the wiper of the starter-switch, operating circuit branches also corresponding to each instrument circuit and having multiple terminals arranged in banks on the various switches, wipers on each switch arranged in the local operating circuit of its controlling relay, means associated with each instrument circuit for closing its corresponding starting circuit branch and opening its operating circuit branch, and means for advancing the starter-switch after one switch has been operated to render another switch in condition to be operated.

5. In an automatic telephone exchange system, a plurality of subscribers' lines, a line relay for each line, a plurality of finder and selector switches, a relay for each finder switch, a starting circuit for the finder jointly controlled by the said relays to produce a momentary current in the starting circuit, and means to restore the switches on the completion of a communication, substantially as described.

6. In an automatic telephone system, a plurality of subscribers' lines, finder switches less in number than the number of lines, and means for operating said finder switches to find the line when said line is closed, selector switches connected to said finder switches, and two magnets for said selector switches adapted to be operated over opposite sides of the connected line, one of said magnets being arranged to produce a long step over a series of contacts in said switch and the other magnet being arranged to produce a series of short steps to terminals of the lines passed over by the long steps.

7. A telephone exchange system comprising a plurality of telephone lines, a plurality of selecting switches each having access to said lines, a master switch for selecting and starting idle selecting switches to establish connection with calling lines, means actuated by a selected selecting switch prior

to its final selecting movement to free said master switch for further use, and means for actuating said master switch once and once only per call.

5 8. A telephone exchange system including telephone lines, a plurality of selectors each having access to said lines, a master switch for starting idle selectors to establish connection with calling lines, a starting circuit 10 normally extending from said master switch to an idle selector, and means actuated by a started selector prior to the final selecting movement to free said master switch for further use.

15 9. A telephone exchange system including telephone lines, a plurality of selectors each having access to said lines, a master switch for starting idle selectors to establish connection with calling lines, a starting circuit 20 normally extending from said master switch to an idle selector, and means for adjusting said master switch and connections altered by a started selector prior to its final selection to free said master switch for further 25 use, said means then serving to adjust said master switch to establish a starting circuit extending to another idle selector.

10. In a switching mechanism, the combination with a plurality of terminals, a 30 branch circuit leading from each terminal, a contact element coöperating with the terminals, and a spring operated device for advancing the element, of a motor magnet for setting the device in actuated position 35 against the tension of the spring, a circuit controlling the operation of the motor magnet which is completed over one or another of the circuit branches upon each advancement of the contact element to effect the energizing of the motor magnet and means for 40

subsequently breaking said circuit to effect the deenergizing of the motor magnet and a source of current supply for said circuits.

11. The combination with a plurality of lines, of a plurality of finder switches for 45 making connection therewith, a starting circuit adapted to be closed by any of said lines in calling and adapted to start one of said switches, means made operative at the outset of the movement of said switch for advancing said starting circuit to the next switch, and means for preventing said calling line from starting said next switch.

12. The combination with a plurality of lines, of a plurality of finder switches for 55 making connection therewith, a starting circuit with which one of said switches is in operative relation, means actuated by any line in calling for closing said starting circuit to start said switch, means actuated by 60 said switch at the beginning of its movement for bringing another finder switch into operative relation with said starting circuit, and means for depriving said calling line of control of said starting circuit before said 65 second switch comes into operative relation with said starting circuit.
